UNITED STATES PATENT OFFICE

2,266,146

OFF-PEAK WATER HEATING SYSTEM

Herman M. Biebel, Elgin, Ill., assignor to McGraw
Electric Company, Elgin, Ill., a corporation of
Delaware

Application October 17, 1940, Serial No. 361,510

8 Claims. (Cl. 219—39)

My invention relates to hot water tanks and particularly to off-peak water heating systems to be used with domestic hot water tanks.

One of the objects of my invention is to provide a relatively simple water heating system embodying a minimum number of elements whereby to control the energization of a hot water tank heating element.

Another object of my invention is to provide an off-peak water heating system, controlled primarily by a constantly operating clock or timing means which will ensure heating of at least the major portion of the water in a tank during the off-peak period.

Another object of my invention is to provide an off-peak water heating system embodying means for delaying energization of the heater if the tank contains more than a predetermined amount of hot water at the start of an off-peak period and which includes also means ensuring the continuation of energization of the electric heating element after the end of an off-peak period if the tank contains an appreciable amount of cold water at the end of an off-peak period.

Other objects of my invention will either be apparent from a description of one form of system embodying my invention or will be pointed out in the course of such description and will be particularly set forth in the appended claims.

In the single sheet of drawing:

Figure 1 is a view showing schematically my improved system applied to an ordinary domestic hot water tank, the latter being shown in vertical section, and,

Fig. 2 is a fragmentary view showing more particularly the control elements in a different position than that in which they are shown in Fig. 1 of the drawing.

I have illustrated a hot water tank 11 of the elongated cylindrical type usually used in domestic installations, this tank being provided with a bottom inlet pipe 13 for cold water and a top outlet pipe 15 for hot water. The tank may be surrounded with heat insulating material 17 and this may be encased in an outer sheet metal casing 19, all of these elements being old in the art and constituting no part of my invention. While I have illustrated specific forms of tank elements, my invention is not to be considered as being limited to the form shown in the drawing.

I provide also a continuously operative timing means designated in its entirety by the numeral 21 this including an electric motor 23 of the kind now used on electric circuits for operating timers. This motor is energized by being continuously

connected to the respective conductors 25 and 27 of a suitable supply circuit of electric energy.

The motor 23 drives a circular disc 29 as by a worm 31, the disc 29 being mounted on a shaft 33 which shaft is to be considered as being suitably supported in bearings not shown in the drawing. I provide further a cam disc 35 on the shaft 33, the outer radius of the major portion of this disc being of one dimension and the radius of a portion 37 being of slightly larger dimension and having a peripheral extent in accordance with the length of off-peak period, as desired by the central station or utility to which the system embodying my invention is to be connected. It is to be understood that shaft 33 and the parts mounted thereon will be turned through one complete revolution in twenty-four hours and I have illustrated the peripheral extent of the portion 37 as being substantially one-third of the total periphery of the disc 35 so that the off-peak period is to be considered as extending over substantially eight hours. At the same time I may, for illustrative purposes, mention that the position of the disc 35 shown in Fig. 1 of the drawing is that 23 which it might occupy at 10 p. m. so that the duration of an off-peak period of eight hours would be from 10 p. m. to 6 a. m.

While I have illustrated a specific form of timing device which may include, although not shown, a timer dial indicating the time of day, I may use any other form of construction of similar elements effective for the same purpose, namely, so far as has already been described, to cause closure of a control switch at the start of an off-peak period and to cause opening of said switch at the end of an off-peak period. While not shown it is to be understood that disc 35 may be adjustably mounted on its support, in this case the shaft 33, so that the beginning and the end of an off-peak period may be made other than that hereinbefore mentioned.

I provide a control switch designated by the numeral 39, to be controlled or actuated by the timing device and which includes a substantially rigid contact arm 41 and a resilient contact arm 43 which latter is adapted to be operatively engaged by the portion 37 of the disc 35 to cause engagement of the arm 43 with the arm 41 at the start of an off-peak period, to remain in engagement therewith during the entire off-peak period and then to be permitted to move out of engagement with contact arm 41 by reason of the bias inherent in contact arm 43 tending to cause such disengagement after the end of an off-peak period.

I provide further a third cam disc 45 on shaft 33 which may also be adjustably mounted thereon and which includes a lug 47 extending radially outwardly beyond the rest of the periphery of substantially uniform radius. I provide also an adjustably mounted arm 49 movable on the shaft 33 but fixed in any desired position by means not shown in the drawing.

The arm 49 carries a second control switch 51 which includes a relatively rigid contact arm 53 and a resilient contact arm 55 normally biased out of engagement with arm 53 by its own construction, but moved into engagement with arm 53 by the ear or lug 47 when this lug operatively engages arm 55. I may provide stop pins 57 and 59 in order to limit the peripheral turning movement of manually adjustable arm 49 to certain specified lengths of time relatively to the other parts of the timing device.

The tank 11 is provided with an electric heating element 61 which may be of any suitable or desired kind and is here shown generally only as including a resistor conductor suitably supported in an annular tunnel 63. I do not desire to be limited to this construction since any kind of electric resistor element may be employed by me.

I provide a single electromagnetic contactor 65 which includes an energizing coil 67, a pair of fixed contact members 69 and a movable contact bridging member 71, all of a kind well known in the art. The supply circuit conductor 25 is connected by a conductor 73 with one of the fixed contacts 69 while the other fixed contact member 69 is connected by a conductor 75 with one end of heating element 61, the other end of which is connected by a conductor 77 with supply circuit conductor 27. When the contact bridging member 71 is in the position shown in the full lines in Fig. 1 of the drawing, the heating element 61 will be traversed by an electric current causing heating of the water in the tank.

Means for causing energization of the coil 67 of the electromagnetic contactor 65 includes, in addition to the switch 39, an auxiliary or upper thermally actuatable switch 79 which includes a tubular member 81 properly connected to the wall of the tank 11 to be located within the tank and to be surrounded by the water in the tank. An expansion rod 83, shown schematically only, is supported by the tubular member 81 and is adapted to cause movement of a resilient contact arm 85 which is adapted to engage with and be disengaged from a relatively rigid contact arm 87. In the position shown in Fig. 1 of the drawing, the tubular member 81 is surrounded by relatively cold water so that the expansion rod 83 is contracted with the result that contact arm 85 is in engagement with contact arm 87. I desire it to be understood that the showing of this thermally actuatable switch subject to the temperature of the water in an intermediate portion of the tank is schematic and illustrative only and that any other suitable kind of thermally actuatable switch effective for the same purpose may be utilized by me and also that this auxiliary thermal switch may be positioned higher up or lower down in the tank than where shown.

Supply circuit conductor 25 is connected by a conductor 89 with contact arm 43 while contact arm 41 is connected by a conductor 91 with contact arm 85. Contact arm 87 is connected by a conductor 93 with one terminal of coil 67, the 75

other terminal of which is connected through a conductor 95 with conductor 77.

Let it be assumed that the timing device has caused movement of the parts operated thereby 5 to the positions shown in Fig. 1 of the drawing and particularly has just caused closure of switch 39. Let it be assumed also that the amount of hot water in the tank 11 is a relatively small quantity so that its lower level is above tubular member 81 whereby tubular member 81 is surrounded by relatively cold water with the result that contact arms 85 and 87 are in engagement as shown in Fig. 1 of the drawing. An energizing circuit through coil 67 of contactor 65 will therefore have been closed, substantially as follows: From conductor 25 through conductor 89, contact arms 43 and 41, conductor 91 through engaged contact arms 85 and 87, through conductor 93 to coil 67 and through this coil and conductors 95 and 77 to the other supply circuit conductor 27. The contactor 65 will therefore be energized and the contact bridging member 71 will be moved from its lowered position, shown by the broken lines in Fig. 1 of the drawing, to its upper or closed position shown by the full lines whereby an energizing circuit, through heating element 61 is closed substantially as follows: From supply circuit conductor 25 through conductor 73 through the contact members 69 and the bridging member 71, conductor 75, heating element 61 and conductor 77 to the other supply circuit conductor 27. This means that energization of the heating element 61 will be started at the start of an off-peak period provided that the amount of hot water in the tank is less than a predetermined minimum, the amount of such cold water being the proportional amount in accordance with the position of the auxiliary thermally actuatable switch 79 relatively to the height of the tank. It is within the province of my invention to place the auxiliary thermally actuatable switch in either the position shown in Fig. 1 of the drawing or higher or lower in the tank and this, of course, will have an effect upon the relative quantity of hot water in the tank and its action upon the auxiliary switch 79.

If, on the other hand, at the time of the start of an off-peak period when contact arms 43 and 41 have been moved into engagement, the amount of hot water in the tank is such that its lower level extends well below the thermally actuatable switch 79, rod 83 will have been expanded as to length and will have moved contact arm 85 out of engagement with arm 87 so that the hereinbefore described energizing circuit through coil 67 cannot be effected through switch 39 at the start of the off-peak period.

It is possible for the operator or user of a water heating system of the kind herein described to ensure start of energization of the heating element at any preselected time during the off-peak period at his will, this being done by manual movement of the arm 49 carrying the switch 51. Let it be assumed that the arm 49 has been moved to the position shown in full lines in Fig. 1 of the drawing and let it be assumed that the position of disc 45 on shaft 33 was such that contact arm 55 was moved into engagement with arm 53 at the start of an off-peak period. In this case an energizing circuit will be closed through coil 67 as follows: From supply circuit conductor 25 through conductor 89, contact arms 43 and 41, conductor 97, contact arms 55 and 53, conductor 99 to one terminal of coil 67 through

the coil and then through conductors 95 and 77 to the other supply circuit conductor 27. It is thus evident that an energizing circuit through coil 67 of contactor 65 will be closed at the start of an off-peak period irrespective of the condition of the thermally actuatable switch 79, that is, irrespective of whether contact arms 85 and 87 are in engagement with each other or not.

A holding circuit for the contactor coil 67 is as follows: From conductor 25 through conductor 89, contact arms 43 and 41, conductor 91, contact arms 85 and 87, conductor 93, coil 67 and conductors 95 and 77 to the other supply circuit conductor 27. It is evident that this holding circuit is not of major importance to hold the contactor 65 in circuit closing position since the latch 103 engaging hook end 101 causes contact bridging member 71 to be held in engagement with fixed contact members 69, so that disengagement of contact arms 85 and 87 because of submersion of tubular member 81 in hot water, and opening of the above described holding circuit would not cause opening movement of bridging member 71.

Let it be supposed, however, that the amount of hot water in the tank at the start of an off-peak period was sufficient to extend below the level of tubular member 81 and that contact arm 85 was out of engagement with contact arm 87 and further that the operator had moved arm 49 in a clockwise direction to call for a delay of say three hours, which position of arm 49 and of switch 51 is shown by the broken lines in Fig. 1. No energizing circuit through coil 67 or through heating element 61 will be closed at the start of an off-peak period and only after the lapse of an adjustably predetermined time, determined by the will of an operator, will contact arm 55 be moved into engagement with contact arm 53 to cause energization, as hereinbefore described, of coil 67 with resultant energization of heating element 61.

I wish to point out here that if the amount of hot water in the tank at the start of an off-peak period was such as to have the tubular member 81 surrounded by hot water but withdrawals of hot water during the hereinbefore described delay period should occur causing the tubular member 81 to be surrounded by cold water, energization of coil 67 of contactor 65 will immediately occur (with resultant energization of heater 61) irrespective of the fact that contact arm 55 of switch 51 is still out of engagement with contact arm 53, this being caused by engagement of the contact arms 85 and 87.

The contactor 65 includes, in addition to the parts already described, a hook-shaped upper end 101 suitably secured to the armature core structure usually provided in electric magnetic contactors. A latch member 103 is normally yieldingly biased into engagement with the hook-shaped end of member 101 by a compression spring 105 which engages an armature core member 107, the latch 103 being suitably secured thereto to be actuated by the armature core 107, when a coil 109 surrounding the same is energized, core 107 to be moved in a right-hand direction as seen in Fig. 1 of the drawing, to cause release movement of latch 103 under predetermined operating conditions to be set forth. I may provide a supporting and stop pin 111 associated with latch 103 which is so shaped that its horizontal movement in either direction will be limited by pin 111.

Means to control the energization of coil 109

comprises a main thermally actuatable switch 113 which may be of the same general type and construction as switch 79. I have illustrated a tubular member 115, a relatively rigid contact arm 117 and a resilient contact arm 119 normally yieldingly biased out of engagement with arm 117 but adapted to be moved into engagement therewith by an expansion rod 121 supported within tubular member 115.

A conductor 123 connects one terminal of coil 109 to contact arm 119 while a conductor 125 connects the other terminal of coil 109 to the left-hand fixed contact member 69 and to conductor 75.

The latch member 103 will, as has already been hereinbefore set forth, be biased to its left-hand or latching position by reason of the biasing spring 105 and if and when coil 67 of contactor 65 is energized as hereinbefore described, the upper hook-shaped end 101 is adapted to move past the left-hand end of latch 103 which is beveled for that purpose, so that when coil 67 has been energized and has caused quick upward movement of contact bridging member 71 and the upper hook end 101 into the positions shown in Fig. 1 of the drawing, these parts will be held in this position by latch 103.

Let it now be assumed that tubular member 115 is surrounded by hot water, that is, water which has been heated to a predetermined and preferably adjustable temperature value whereby expansion rod 121 has been expanded sufficiently to cause engagement of contact arm 119 with contact arm 117, an energizing circuit through coil 109 will be closed extending substantially as follows: From supply circuit conductor 25 through conductor 73, contact member 69 and contact bridging member 71 through conductor 125, coil 109, conductor 123, through contact arms 119 and 117 and through conductor 77, to the other supply circuit conductor 27. This energization of coil 109 will cause quick right-hand movement of core 107, resulting compression of spring 105 and right hand movement of latch 103 with the result that contact bridging member 71 will drop into its lowered or open circuit position to cause deenergization of the heater 61.

Should deenergization of the heating element 61 occur during the rest of the off-peak period after the manually adjustable switch 51 has been closed, as hereinbefore described, and should withdrawal of hot water occur thereafter during the off-peak period, it is evident that reenergization of coil 67 and therefore of heater 61 will occur if the withdrawal of hot water is to such an extent that auxiliary thermally actuatable switch 79 is subjected to cold water, all of this being evident from the action thereof, as hereinbefore described.

Fig. 2 of the drawing shows the positions of the various parts of my improved water heating system and of its respective elements when the tank is full of hot water at the end of an off-peak period. It is to be noted, however, that if the tank is not entirely full of hot water at the end of the off-peak period so that thermally actuatable switch 113 is in the position shown in Fig. 1 of the drawing, that energization of heater 61 will continue beyond the end of the off-peak period even though contact arm 43 is permitted to move out of engagement with contact arm 41 and into the position shown in Fig. 2 of the drawing. This energization of heater 61 will continue for as long as the lower thermally actuatable switch 113 is subjected to the temperature

of cold water or of water below a predetermined temperature. It is evident that this prolonged or continued energization of coil 61 beyond the end of an off-peak period will continue until all of the water in the tank is hot. When the heater 61 has once been deenergized after the end of an off-peak period, as hereinbefore set forth, reenergization thereof cannot occur until the start of the next off-peak period.

The system embodying my invention thus provides a relatively simple means including relatively few parts for ensuring starting of the energization of a tank heater at the beginning of an off-peak period if the tank contains more than a predetermined amount of cold water at the start of an off-peak period, that will delay energization of the heater for a selected manually adjustable time in case the tank contains more than a predetermined amount of hot water at the start of an off-peak period, that will cause energization of the heater during the delay period if more than a predetermined quantity of hot water is withdrawn from the tank during the delay period, that will cause deenergization of the heater at any time during an off-peak period if all of the water in the tank has been heated to a predetermined temperature, that will reenergize the heater during the rest of an off-peak period if withdrawals of hot water occur and that will prolong energization of the heater beyond the off-peak period in case all of the water in the tank is not hot at the end of the off-peak period.

It may also be here pointed out that the single heater-controlling electromagnetic contactor is controlled as to its closing movement by means controlled solely by time or by the joint action of means controlled by time and by the temperature of an intermediate part of the tank contents and that the opening movement of the contactor is effected by means responsive to the temperature of the water in the lower portion or at the bottom of the tank.

While I have illustrated and described a specific embodiment of water heating system embodying my invention, it is obvious that modifications may be made therein and all modifications clearly coming within the scope of the appended claims shall be considered as being covered thereby.

I claim as my invention:

1. An off-peak water heating system for a water tank comprising an electric heater, a magnetic contactor controlling the electric circuit of the heater, means including a time-controlled switch held in closed position during an off-peak period of fixed length to cause energization of the contactor and of the heater, an electromagnetically controlled latch normally yieldingly biased into a position to hold the contactor in circuit closing position and thermally controlled means subject to the temperature of the water in the tank to cause release movement of the latch to cause deenergization of the electric heater when substantially all of the water in the tank is hot.

2. An off-peak water heating system for a hot water tank comprising an electric heater, an electromagnetic switch controlling said electric heater, a continuously operative timer, switching means severally controlled by the timer and by the temperature of the water in a certain part of the tank to cause closure of said electromagnetic switch at a predetermined time, an electromagnetically controlled latch normally yieldingly biased into position to hold said electromagnetic

switch closed and a thermally actuable switch for causing releasing movement of said latch when substantially all of the water in the tank is hot.

3. An off-peak water heating system for a hot water tank comprising an electric heater, an electromagnetic switch controlling the energization of said heater, a continuously operative timer, a switch adapted to be held closed by said timer during an off-peak period of predetermined duration, a thermally actuable switch subject to the temperature of the water at a certain point in the tank, electric connections between the timer-controlled switch, the thermally actuable switch and said electromagnetic switch to cause energization of the electric heater at the start of the off-peak period when the thermally actuable switch is subject to water temperature below a predetermined value, an electromagnetically-controllable latch normally spring biased into position to hold said electromagnetic switch closed and a second thermally actuable switch subject to water temperature at another point in the tank for causing release movement of the latch when the temperature of the water at said other point is above a predetermined value and consequent deenergization of the electric heater irrespective of the position of said timer-controlled switch.

4. An off-peak water heating system for a hot water tank comprising an electric heater, an electromagnetic switch controlling the energization of said heater, a continuously operative timer, a switch adapted to be held closed by said timer during an off-peak period of predetermined duration, a thermally actuable switch subject to the temperature of the water at a certain point in the tank, electric connections between the timer-controlled switch, the thermally actuable switch and said electromagnetic switch to prevent energization of the electric heater at the start of the off-peak period in case said thermally actuable switch is subject to water temperature above a predetermined value, a manually adjustable second timer-controlled switch adapted to be closed momentarily by said timer at a selected time after start of an off-peak period and closing of said first timer-controlled switch, said two timer-controlled switches being jointly effective to cause closing of said electromagnetic switch and energization of said heater, a latch normally spring biased into position to hold said electromagnetic switch in closed position, electromagnetic means on said latch to cause release movement of said latch and a second thermally actuable switch subject to water temperature at another part of the tank for causing energization of the electromagnetic latch release means, opening of the electromagnetic switch and deenergization of the electric heater irrespective of the position of said first named timer-controlled switch.

5. An off-peak water heating system for a hot water tank comprising an electric heater, an electromagnetic switch controlling the electric heater, a continuously operative timer, means including a plurality of timer-controlled switches and a thermally actuable switch responsive to the temperature of the water in a predetermined part of the tank to selectively cause energization and closure of the electromagnetic switch and energization of the heater at the start of an off-peak period in case the thermally actuable switch is subject to a water temperature below a given value and energization and closure of the electromagnetic switch and energization of

the heater at an adjustably fixable later time in case the thermally actuable switch is subject to a water temperature above said given value, an electromagnetically releasable latch normally yieldingly biased into position to hold said electromagnetic switch in closed position and a second thermally-actuable switch in the lower part of the tank to cause release movement of said latch, opening of said electromagnetic switch and deenergization of said heater when said second thermally actuable switch is responsive to a water temperature above a predetermined value.

6. An off-peak water heating system for a hot water tank comprising an electric heater, an electromagnetic switch for said heater and means including a plurality of time and temperature controlled switches for controlling the energization and deenergization of said electromagnetic switch to selectively cause energization of the heater at the start of an off-peak period in case of the presence of more than a predetermined quantity of cold water in the tank at the start of an off-peak period, to cause continuance of the energization of the heater beyond the end of an off-peak period in case of the presence of more than a predetermined quantity of cold water in the tank at the end of an off-peak period and to cause deenergization of the heater when the tank is full of hot water.

7. An off-peak water heating system for a hot water tank comprising an electric heater, an electromagnetic switch for said heater and means including a plurality of time and temperature controlled switches for controlling the energization and deenergization of said electromagnetic switch to preclude energization of the heater for an adjustably predetermined length of delay time after the start of an off-peak period in case of the presence in the tank of less than

a predetermined amount of cold water at said time, to cause energization of the heater during said delay time in case withdrawal of hot water from the tank causes the tank to contain more than said predetermined amount of cold water, to cause continuance of the energization of said heater after the end of the off-peak period in case of the presence in the tank of more than said predetermined amount of cold water at the end of said off-peak period and to cause deenergization of said heater when substantially all of the water in the tank is hot.

8. An off-peak water heating system for a hot water tank comprising an electric heater, an electromagnetic switch for said heater and means including a plurality of time and temperature controlled switches for controlling the energization and deenergization of said electromagnetic switch to selectively cause energization of the heater at the start of an off-peak period in case of the presence of more than a predetermined quantity of cold water in the tank at the start of an off-peak period, to preclude energization of the heater for an adjustably predetermined length of delay time after the start of an off-peak period in case of the presence in the tank of less than a predetermined amount of cold water at said time, to cause energization of the heater during said delay time in case withdrawal of hot water from the tank causes the tank to contain more than said predetermined amount of cold water, to cause continuance of the energization of said heater after the end of the off-peak period in case of the presence in the tank of more than said predetermined amount of cold water at the end of said off-peak period and to cause deenergization of said heater when substantially all of the water in the tank is hot.

HERMAN M. BIEBEL.
